E. F. AND J. F. CONNELL.
STOP MOTION.
APPLICATION FILED JAN. 4, 1921.

1,423,398.

Patented July 18, 1922.

Fig. 1.

UNITED STATES PATENT OFFICE.

EDWARD FRANCIS CONNELL AND JOHN FRANCIS CONNELL, OF FLORENCE, MASSACHUSETTS.

STOP MOTION.

1,423,398.

Specification of Letters Patent. Patented July 18, 1922.

Application filed January 4, 1921. Serial No. 434,977.

To all whom it may concern:

Be it known that we, EDWARD F. CONNELL and JOHN F. CONNELL, citizens of the United States, and residents of Florence, in the county of Hampshire and State of Massachusetts, have invented a new and Improved Stop Motion, of which the following is a full, clear, and exact description.

Our invention relates to stop motions, and 10 more particularly to stop motions of the kind in which one or more electric circuits normally closed, are opened as a means of controlling the stoppage of the machines with which the stop motion is associated.

15 More specifically stated, our invention relates to stop motions suitable for use upon looms, knitting machines and other devices for manufacturing fabrics and in which the stop motion is under the control of a thread, 20 normally taut.

Our invention contemplates means for actuating the stopping motion whenever any one of several distinct troubles arises in connection with the thread used for controlling 25 the stop motions.

In this connection it may be stated that for the purposes contemplated by our invention the stop motion should be actuated whenever it happens that the controlling 30 thread becomes exhausted or breaks, or for any reason becomes too tight, or if it carries a knot or a tangle such as would ordinarily be objectionable.

Reference is made to the accompanying 35 drawing forming a part of the specification in which like reference characters indicate like parts through the several views, and in which—

Figure 1 is a front elevation of our improved stop motion.

Fig. 2 is a side elevation of the same.

Fig. 3 is a section on the line 3—3 of Fig. 1, looking in the direction indicated by the arrow.

Fig. 4 is a plan view of our device.

A supporting board is shown at 1 and has generally the form of a standard, which is provided with an arm 2 of substantially L-shape located at its bottom and extending laterally from it as may be understood more particularly from Figs. 2 and 3. The arm 2 carries two leaf springs 3, 4, which

are provided with a contact 5, controllable by an adjusting screw 6, as indicated more particularly in Fig. 2. Staple guides 7, 8 are mounted upon the board 1 and spaced apart. The thread used for controlling the stop motion appears at 9 and travels through the guides 7, 8. A friction lug is shown at 10 and is provided with a semi-cylindrical portion 11 at the upper end portion of the spring 3. A stationary arm 13 made preferably of stout wire is secured to the board 1 and extends obliquely upward therefrom as indicated in Figs. 1 and 2. The upper end portion of this arm 13 is formed into a V-bearing 12 for supporting the thread 9. A contact arm 14 is secured directly upon the board 1 and above this contact arm is a bearing 15. Supported upon the bearing 15 is a swinging arm 16 provided with two eyes 17, 18, through which the thread 9 passes. A tension bar 19 is mounted upon the upper end of the board 1 and is engaged by the thread 9. An eye 20 through which the thread 9 extends, is mounted upon a leaf spring 21, this leaf spring being secured upon the upper end portion of a metallic post 22, this post being mounted directly upon the board 1 and extending upwardly therefrom.

A metallic tongue 23 is supported by the post 22, and is insulated therefrom by a plate 24 of hard rubber or other appropriate insulating material. Extending through the metallic tongue 23 is a contact screw 25 which is so positioned as to be easily engaged by the contact spring 21 when the latter is drawn down into its abnormal position, as indicated by dotted lines in Fig. 2. A binding post 26 is mounted upon the metallic tongue 23 and is connected with a wire 27. This wire leads to another binding post 28, which is mounted directly upon the back of the board 1. A wire 29 leads from the binding post 28 to another binding post 30 and from the latter a wire 31 leads to the spring 4. Another wire 32 leads from the spring 3 to a binding post 33. From this binding post a wire 34 leads to a battery 35, or other appropriate source of electricity. A wire 36 is connected with the binding post 30. The wires 36 and 34 together with the battery 35 are used for controlling the stoppage of the

machine. This feature being old and well known we will not describe. A wire 37 leads from the binding post 33 to another binding post 38. This binding post being provided with a bolt 39, extends through the board 1 and engages the contact arm 14. A wire 40 leads from the binding post 38 to the metallic post 22.

The thread 9 is located between the bobbin 10 and the carrier, as is customary in this art. The thread being in position, as shown, and being under tension, the various electrical contacts are open as may be understood from Fig. 2. The swinging arm 16 and the contact arm 14 together constitute a contact which is normally open as indicated by full lines in Fig. 2, but which may be closed as indicated by dotted lines in said figure. The contact between the screw 25 and the leaf spring 21 is normally open, as indicated by full lines in Fig. 2. This is also true of the contact 5 between the leaf spring 3 and the screw 6, as indicated at the lower right hand portion of Fig. 2.

Our device is constructed and arranged so that the closing of any one of the contacts above described will energize the circuit containing the wires 34 and 36 and the battery 35, the circuit thus energized being so arranged as to control the stoppage of the machine with which the stop motion is associated.

The operation of our device is as follows: The various parts are constructed and arranged as above described, the thread 9 being under tension and being drawn through the device, the various contacts are all open.

Suppose now that for any reason the thread 9 becomes too tight the leaf spring 21 is bent downwardly, as indicated by dotted lines in Fig. 2, so as to be brought into contact with the screw 25; a circuit thereby being completed as follows: battery 35, 40 wire 34, binding post 33, wire 37, binding post 38, wire 40, metallic post 22, contact spring 21, contact screw 25, metallic tongue 23, binding post 26, wire 27, binding post 28, wire 29, wire 36, to electrically operated mechanism (not shown) used for stopping the machine, thus back to battery 35.

Suppose next that the thread breaks or that the supply of thread becomes exhausted; such being the case the swinging arm 16 drops down by its own weight from its position indicated by full lines in Fig. 2 to its position indicated by dotted lines in said figure, and by so doing comes into contact with the contact arm 14. Another circuit is thus completed as follows: battery 35, wire 34, binding post 33, wire 37, bolt 39, contact arm 14, swinging arm 16, binding post 28, wire 29, binding post 30, wire 36, to electrically operated mechanism for stopping the machine, thence back to battery 35.

Suppose next that the thread 9 carries a knot or tangled portion of thread; as the thread travels this knot is drawn in between the contact spring 3 and the friction guide 11. Owing to the size of the knot or tangle 70 the contact spring 3 is forced to the right according to Fig. 2, and thus into engagement with the contact screw 6. An electrical circuit is thus closed as follows: battery 35, wire 34, binding post 33, wire 32, 75 contact spring 3, contact 5, contact screw 6, spring 4, wire 31, binding post 30, wire 36, to electrically operated mechanism for stopping the machine, thence back to battery 35.

Thus it will be seen that the stop motion mechanism is operated automatically in the event that either the thread becomes too tight, or is broken or exhausted, or contains a knot or tangle.

We do not limit ourselves to the precise mechanism shown as variations therein may be made without departing from our invention, the scope of which is commensurate with our claims.

We claim:

1. In an electrically operated stop motion, the combination of a standard, a contact leaf spring carried by the standard, said spring being secured at one end and adapted to be flexed by the pressure of a thread exerted on the free end thereof, a member also carried by the standard and arranged adjacent the spring, the spring and member extending in the same direction approximately parallel with each other, a contact screw carried by the member and adapted to engage the spring at a point intermediate of its ends when said spring is flexed, and an electric circuit connected with the 95 spring and member.

2. In a stop motion, thread guides, a friction member between the guides, a leaf spring secured at one end and having its free end opposite the friction member and 100 between which member and spring the thread passes, and a member adjacent the spring and having a contact screw adapted to engage the spring at a point intermediate of its fixed end and the friction member 105 when forced away from the friction member by the thread.

3. A device of the character described comprising a board, an L-shaped arm mounted thereupon and extending laterally therefrom, a pair of leaf springs mounted upon said arm, a contact screw extending through one of said leaf springs and into proximity to the other, so that when said last mentioned leaf spring is moved in a particular 110 direction a contact is closed between said leaf springs, and means for conducting a thread against one of said leaf springs.

4. In a device of the character described, a standard provided with spaced thread 115

guides and with a friction member between the guides, a leaf spring secured to the standard and having its free end opposite the friction member of the standard, a member secured to the standard adjacent the spring, a screw mounted in the said member and adapted to be engaged by the spring

at a point intermediate of the ends of the spring when said spring is moved by a thread, and a circuit connected with the 10 spring and member.

EDWARD FRANCIS CONNELL.
